UNITED STATES PATENT OFFICE.

JULIUS HANSEN, OF TEXAS CITY, TEXAS.

APPARATUS FOR EXPRESSING THE FLUIDS OUT OF PARAFFIN COMPOSITIONS AND SEPARATING THE SCALE THEREFROM.

1,054,839.

Specification of Letters Patent.

Patented Mar. 4, 1913.

Application filed November 25, 1911. Serial No. 662,312.

To all whom it may concern:

Be it known that I, JULIUS HANSEN, a citizen of the United States, residing at Texas City, in the county of Galveston and State of Texas, have invented certain new and useful Improvements in Apparatus for Expressing the Fluids Out of Paraffin Compositions and Separating the Scale Therefrom, of which the following is a specification, reference being had to the accompanying drawings.

This invention relates to apparatus for compressing and straining the scales or crystals of paraffin, or of wax of a paraffin nature.

The object of this invention is to provide a machine of the class referred to that will enable the operations of completely straining and removing the oil from paraffin distillate to be done in one machine.

Another object of this invention is to provide a machine for the purpose in question, that will perform in itself the functions of the filter press and scale press.

A further object of this invention is to provide a machine which may be used continuously for the purpose in question.

Other objects of this invention are to provide a machine of the class described which may be readily manufactured and installed at a comparatively low cost, which may be readily inspected and repaired, which will take up a relatively small amount of space, which will have a relatively high efficiency and which will be arranged so that the material within the machine may be tested without interfering in any way with the operation of the same.

Further objects of this invention will become apparent as it is more fully set forth.

The apparatus embodying this invention consists in general of two parts arranged to respectively perform the functions of a filter press and a scale press. A filter press for paraffin consists of an apparatus for removing the loose oil in which the scales or crystals of wax float, and a scale press is used for the purpose of removing the entrained oil and water that is in the compressed scales or crystals after the same has been ejected from the filter press.

The processes performed by the filter press and scale press are ordinarily done in separate machines, which are independent of one another and which make the processes

in question relatively expensive because of the necessary amount of labor required to properly take care of the separate machines. This invention avoids the inconvenience and cost of having separate machines and apparatus for the filtering and scaling processes referred to, as it enables the entire work to be done in one machine which may be operated by a single source of power and so connected up and devised that it may be run continuously, and in addition permit samples of the material acted upon to be taken out and tested without interfering in any way with the proper operation.

The present application involves only the novel structural features of the apparatus by means of which the process above outlined is carried out, the process itself being more specifically described and claimed in my companion application, Serial Number 679,652, filed February 24, 1912.

An embodiment of this invention is shown in the appended drawings, in which,

Figure 1 represents a view in elevation of an apparatus embodying this invention. Fig. 2 is a plan view of Fig. 1. Fig. 3 is a sectional view taken along the line 3—3 of Fig. 1. Fig. 4 is a sectional view taken along the line 4—4 of Fig. 3.

Similar reference characters refer to similar parts throughout the drawings.

In the construction shown in the drawings, 1 and 1' designate the casings of the parts of the device which perform functions of a filter press and scale press respectively. Each casing is preferably constructed as shown in the drawings, and both are very similar to one another. The casing 1 is however preferably provided with straining sheets 2 and 3 which are somewhat coarser than 2' and 3' in the casing 1' of the scale press part. The straining sheets 2 and 2' are preferably made of some suitable straining cloth, and are attached to metallic screens 3 and 3' which are preferably of cylindrical shape and surround the first mentioned straining sheets. A plurality of rings 4 and 4' secure said straining sheets to the screens as is clearly shown in the drawings. Suitable pipes 5 and 5' surround the screens 3 and 3' and securely hold the latter in position by means of rings 6 and 6' which are held in place by means of bolts 7 and 7'. The casings 1 and 1' surround and contain the pipes

5 and 5', and are provided with annular chambers 8 and 8' which permit the fluids strained from the material that passes through the parts in question, to flow therein, and by means of suitable connections to be removed therefrom. The casings are also provided with annular chambers 9 and 9' for the purpose which will be explained in a later part of the specification.

10 The casing 1 is provided with an end piece 10 that is provided with an inlet opening 11 therein, which is suitably connected so as to receive the distillate to be processed. In some convenient part of the end piece 10, a 15 valve 12 is provided for testing purposes. At the other end of the casing 1 is another end member 13 that is provided with an outlet opening 14 therein, and a testing valve 15 for the purpose of sampling the material 20 at that portion of the casing. The members 10 and 13 are preferably threaded on to the ends of the pipe 5 as is clearly shown in the drawings. The end members are also provided with holes and stuffing boxes 16 and 25 17 respectively for the purpose of permitting the worm shaft 18 to project therethrough, so that the latter can be suitably coupled to a source of power, and journals 19 and 19' are provided for the purpose of 30 supporting the same, and thrust bearings 20 are arranged for the purpose of keeping said worm shaft properly in position.

The casing 1' is provided with parts very similar to those used in connection with the 35 casing 1, and are designated by similar characters with a prime ('), added thereto, in order to facilitate the recognition of their connection with the apparatus. The shafts 18 and 18' are preferably connected to one 40 another by means of a suitable coupling 21, or if desirable or necessary, this coupling can be replaced by suitable gearings. The outlet valve of casing 1 and the inlet valve of casing 1' are connected by means of suitable pipe connections 22, and suitable valves 45 23 and 24 are provided thereon, so as to control the flow of material therethrough and also to permit the repair or inspection of the various parts of the apparatus. 50 Other valves 25 and 26 are provided upon the inlet connections of casing 1 and the outlet connections 27 respectively for similar purposes. The casings 1 and 1' are provided with suitable connections 28 and 29 55 for the purpose of attaching the same to apparatus which are used for causing the flow of suitable fluids through the chambers 9 and 9' in the casings 1 and 1' respectively.

60 The apparatus used in connection with casing 1 is preferably of a freezing or cooling nature and arranged so as to pass a cooling fluid through the annular recesses 9 of the same, in order to bring the distillate 65 in said casing to a suitable temperature.

The apparatus connected with casing 1' is for the purpose of heating the same so that the wax, scales or crystals may be suitably raised in temperature and thereby enable the oil and other fluids therein to be more easily 70 removed. The holes for permitting the fluids to escape through the pipes 5 and 5' are designated by the reference characters 30 and 30', and those in the straining screens by 31 and 31'. The last mentioned holes are 75 preferably out of registry with one another so as to prevent the wax to be separated from the oil from being pushed through the pipes into the chambers 8 and 8' thereof. The screens 3 and 3' are secured in such a manner to said pipes as to permit the oil and other fluids to flow between them to the holes 30 and 30' and thence to the chambers 8 and 8', so that they can be readily removed therefrom and in a state practically 80 free from wax, scale or crystals.

The general operation of the device is as follows:—The distillate is pumped into the casing 1, the outlet valve being closed, and the cooling fluid is run through the casing 90 so that the distillate condenses into oil and scales. Pressure is then exerted so that the material in the casing will tend to flow through the perforations in the screen and through the holes in the pipe 5. The oil will flow through the pipe and into the chamber 8, and thence to a suitable reservoir arranged to receive it. The scales, crystals or wax will be caught by the inner filter cloths 2 and accumulate in the casing until 100 the latter is practically filled, the oil that leaves the same being passed to the reservoir just mentioned. When a certain amount of wax has accumulated in the casing, the valve on the outlet is opened and the wax is permitted to flow to the second press 1', until 105 it fills the same, at the same time more distillate is pumped into the first mentioned casing and sufficient pressure is placed thereon to cause its oil to filter from the same 110 in the manner already described. The worm shaft is then rotated so as to push the wax through the apparatus. The wax in the second casing is then subjected to a high temperature by means of hot water or steam 115 being passed through the annular recesses in the casing 1'. This rising temperature causes the wax to expand and to more freely give up its fluid on the compression. The oils and other fluids in the wax pass through 120 the straining sheet, screen, and pipe as in the first casing, and thence is pumped into another reservoir provided for the purpose of receiving the same. The last mentioned process leaves the wax in a very dry condition and permits the same to be removed 125 from the second casing for commercial purposes. The rotation of the worm shafts continuously pushes the wax through the apparatus and the pressure exerted on the ma- 130

terials, by any suitable means enables the same to strain itself in a manner already described. After the apparatus is once set into action and a sufficient amount of wax is accumulated in a second section of the apparatus and in the rear portion of the first casing, the process can be kept up continuously, provided that the casing 1 is cooled to a proper temperature, to precipitate the crystals therein sufficiently to permit the fluids in the same to strain out, as the pressure that forces the material through the apparatus is exerted. The various testing valves on the front and rear portions of each of the casings enable the material within to be sampled at any time without interfering in any way with the operation of the machine.

While the shafts in both of the casings are preferably run at the same speed, it is of course understood that they can be mechanically made to run at various speeds so as to suit any conditions that may arise. The pressure exerted on the material within the casings may also be varied independently of one another so as to produce the best results from the apparatus. This pressure may be exerted in any suitable way, and it is preferable that in the first casing it should be from two hundred (200) to three hundred (300) pounds per square inch, and in the second casing, 1', from five hundred (500) to six hundred (600) pounds per square inch, provided the ordinary materials are used. However, pressures and temperatures to suit any special conditions can be readily provided for without departing from the scope of this invention, and various other details of constructions may be made in the apparatus to suit any particular conditions met with without departing from the principles thereof.

While it is not new to use processes for filtering and scaling independent of one another, it is new to use such processes in conjunction with one another and arranged so as to act continuously, and further to provide means for permitting the sampling or testing of material within the apparatus without stopping the machine or interfering in some radical way with its operation. A particular advantage is that the various parts are simple in their construction and are easily accessible for inspection and repair and are so arranged that one operator can normally take care of the apparatus. Another feature is that the amount of power required to operate this apparatus is comparatively low, mainly due to the fact that the wax or crystals are not themselves forced through straining sheets, or otherwise made to overcome a very high frictional resistance. The independence of the parts of this machine is another feature of value, as it enables units of various sizes of

the parts of the machine to be installed with one another; for instance, a large filtering casing could be used with a relatively small scaling casing, provided with the gearing that operates the worm shaft is arranged so as to make up in speed what is lacking in volume, and many other conditions can be provided for without radically changing the apparatus in any way. Another feature of importance, which the continuous arrangement of the two processes has, is that it keeps the wax entirely free from atmospheric interference while the process is going on, and thereby prevents the wax and scales from absorbing moisture from the same, while the process is going on. This feature reduces the amount of power required to drive the materials in question and thereby increases the efficiency of the apparatus.

Having thus described this invention, what is claimed is:—

1. An apparatus for separating the wax and fluids from paraffin distillate comprising in combination a casing having an annular chamber therein and provided with a second inner annular chamber, a pipe disposed within said casing and provided with a plurality of holes therein opening into said chamber, a screen having a plurality of perforations therein disposed loosely within said pipe, straining cloths disposed on said screen and means for securing said parts together, a worm shaft disposed in said casing for forcing the solid matter into the same therethrough, another similar casing having parts similar to those in the last mentioned casing, and means for connecting said casings together in series, said means being arranged to permit samples of the material passing therethrough to be taken therefrom.

2. An apparatus for separating the wax and fluids from paraffin distillate comprising in combination a casing having an annular chamber therein and provided with a second inner annular chamber, a pipe disposed within said casing and provided with a plurality of holes therein opening into said chamber, a screen having a plurality of perforations therein disposed loosely within said pipe, the perforations in said screen being arranged out of registry with the holes in said pipe, a straining cloth disposed on said screen and means for securing said parts together, a worm shaft disposed in said casing for forcing the solid material in the same therethrough, a plurality of end pieces disposed on said pipes, said pieces being provided with stuffing boxes therein to permit said shaft to extend therethrough, and means for keeping said end pieces together.

3. An apparatus for separating the wax and fluids from paraffin distillate comprising

4
ing in combination, a casing having inner and outer annular chambers, a pipe concentrically arranged within said casing and spaced from the wall of the chamber, said pipe being provided with apertures, a perforated screen arranged upon the inner wall of said pipe and having its perforations disposed out of register with the apertures of the pipe, a plurality of spaced annular members secured to said screen to retard the

movement of the distillate through the pipe, and a worm shaft disposed centrally within said pipe to force the distillate longitudinally therethrough.

In testimony whereof I hereunto affix my 15
signature in the presence of two witnesses.

JULIUS HANSEN.
